UNITED STATES PATENT OFFICE

2,049,671

ELECTROLYTIC CONDENSER

Julian K. Sprague, Quincy, Mass., assignor, by
mesne assignments, to Sprague Specialties
Company, a corporation of Massachusetts

Application November 19, 1930, Serial No. 496,762

3 Claims. (Cl. 175—315)

My invention relates to electrolytic condensers and the like.

Devices such as electrolytic condensers in various applications, for instance, when used as parts 5 of radio receiving sets, must be of compact and rigid construction, must afford easy and convenient mounting, and have liquid and airtight sealing.

The object of my invention is to provide for a 10 mode of construction of such devices, which fulfills all of the above requirements.

I shall illustrate my invention in connection 15 with electrolytic condensers. However, it should be well understood that my invention is not limited to such devices.

In the accompanying drawing, which forms part of this specification, Figure 1 is a side elevation, partly in section, showing one embodiment of my invention.

20 Fig. 2 is a fractional side elevation, partly in section, showing another embodiment of my invention.

Referring to Figure 1, the electrolytic condenser there shown consists of a cylindrical container 1, provided on its top and bottom with covers 2 and 3 respectively, hereinafter more fully described, and an electrode 4 which forms the anode of the condenser, supported by the cover 3.

The container 1 which preferably forms the 25 other electrode may be of any suitable material, as an inert or film-forming metal, and contains a suitable electrolyte 5.

Resting on the upper edge of an annular recess 6 provided near the top of the container 1, 30 is the cover 2 which is preferably of insulating material, for instance, hard rubber. The cover 2 which is shown as having an inverted conical shape is provided with a central vertical hole 8 going through its entire height, and connecting 35 with a soft rubber nipple 9 projecting upwardly from the center of the cover. The nipple 9 is provided with a pin hole 10 for the escape of gases which may form during the operation of the device.

40 The cover 2 and the nipple 9 may be made integral, as described in the copending application, Ser. No. 451,029 of C. Shugg and P. Robinson, filed on May 9, 1930, now Patent No. 1,895,738.

On its upper periphery the cover 2 is provided 45 with an annular recess 11 to carry a soft rubber gasket 12. The free end of the container 1 is spun around the gasket 12 and constitutes therewith a liquid and air-tight seal.

The lower cover 3 substantially a disc of insulating material, for instance hard rubber, is pro-

vided with a downwardly extending cylindrical portion 13, this extension being provided with a—preferably coarse—outside thread. The upper face of the cover 3 abuts against the lower shoulder of an annular recess 7 provided near the bottom of the container. On its lower face the cover 3 is provided with a peripheral recess 14 adapted to receive a soft rubber gasket 15 around which the lower free end of the container 1 is spun, to form therewith a liquid and air-tight seal. The 10 cover 3 is provided with a metal insert molded therein, consisting of a cup shaped portion 16 extending into a stem 17 threaded on its end to carry nuts 18—18.

The insert cup 16 is provided with an internal 15 thread and with a peripheral bead 19 to prevent the loosening of the cup in the cover. The insert 16 may be of any suitable metal, however, a film-forming metal, as aluminum, is preferable.

The anode 4 may be of any suitable construction; for instance, as shown, the anode may be a tube provided with helical corrugations, such anodes being described in the co-pending applications Ser. No. 416,939 of F. Desmond Sprague and R. U. Clark, filed Dec. 27, 1929, now Patent 25 No. 1,958,682 and Ser. No. 441,128 of Max Knab, filed Apr. 2, 1930, now Patent No. 1,983,468, such anodes possessing various advantages, fully described in these applications.

The anode 4 is provided with an extension 20 30 forming a shoulder 21 beyond which the extension is reduced in diameter and threaded at 21a. The threaded portion 21a of the anode is screwed tight into the internal thread of the cup 16.

A metal washer 22 and a gasket 23 is placed 35 between the shoulder 21 and the cover 3, both surrounding the extension 21a.

When the anode stem 21a is screwed into the cup 16 the shoulder 21 of the anode presses against the washer 22 and the gasket 23, whereby the 40 latter forms a leakage-tight seal between the metal insert 16 and the cover 3, should the joint between the two be not sufficiently tight to prevent such leakage.

The condenser so assembled may be mounted on 45 a suitable panel 26 by means of the threaded portion 13 of the cover, which protrudes through the panel 26 and carries a nut 25 by means of which the cover 3 and thus the whole condenser is secured to the panel 26.

The nuts 18—18 and the stem 17 form the 50 electrical terminal of the anode, whereas the container 1 which forms the cathode may be directly grounded to the panel 26 in case the latter is of metal, or if desired, other suitable 55

connections may be made to the container 1. In case it is desired to insulate the container 1 from the panel 26 a suitable insulating washer (not shown) is interposed between the spun-over portion of the container and the panel 26.

In the modification shown in Fig. 2, instead of providing a metal insert in the cover 3a, a central threaded hole 30 is provided therein and the threaded stem 32 of the anode screwed in this hole. The end of the stem 32 hereby projects through the cover and carries the nuts 18-18. It is preferable in this case to make the anode shoulder 33 of a somewhat larger diameter, whereby the anode stem on its shoul- 10 dered end fits in an annular recess 34 of the cover 3a. Placed between the bottom of the shoulder 33 and the top of the recess 34, a washer 35 is provided to prevent leakage around the stem 32.

It is also evident that instead of supporting the condenser by placing it on the top of a panel 26 it may also be supported in a similar way by hanging it down therefrom, nor is my invention limited to electrolytic condensers, but various modifications in construction and application may suggest themselves without deviating from the scope of my invention and the appended claims should be construed therefor as broadly as per- 20 25 30 missible in view of the prior art.

What I therefore claim as new and desire to secure by Letters Patent is:

1. In an electrolytic condenser, a container and an electrode provided with a threaded extension, a cover provided with a metallic insert threaded 5 to receive said electrode, said insert being inwardly flush with said cover and outwardly projecting beyond the cover to form an outside electrical connection for the electrode.

2. In an electrolytic device, a container and a 10 cover of insulating material, said cover being provided with a metallic insert molded therein and being flush at its inner end with the cover, an electrode provided with an extension supported in said metallic insert, and means to form out- 15 side electrical connection for said electrode through said insert.

3. In an electrolytic condenser in combination a metallic container forming one electrode of said device and having a bottom cover of insu- 20 lating material, an interiorly threaded metallic insert within said cover and flush on its inner end with said cover, the outer end of said insert extending beyond said cover, an electrode in said container having a threaded end, said threaded 25 end engaging the threads of said insert, a shoulder on said electrode and a sealing gasket squeez- 30 ingly disposed between said shoulder and the inner face of said insert and cover.

JULIAN K. SPRAGUE. 30
